[57] **CLAIM**

The ornamental design for a keeper for a locking container door, as shown and described.

DESCRIPTION

FIG. 1 is a top, front, and left side perspective view of a keeper for a locking container door showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a vertical cross-sectional view thereof, taken along line A—A of FIG. 2; and,

FIG. 9 is a top, front, and left side perspective view thereof, the broken-line disclosure of a cam being for illustrative purposes only and forming no part of the claimed design.
